(No Model.)

A. LINDQUIST.
GRAVE ALARM.

No. 500,072.

Patented June 20, 1893.

UNITED STATES PATENT OFFICE.

AUGUST LINDQUIST, OF CHARITON, IOWA, ASSIGNOR OF ONE-HALF TO
CHARLES DALIN, OF SAME PLACE.

GRAVE-ALARM.

SPECIFICATION forming part of Letters Patent No. 500,072, dated June 20, 1893.

Application filed February 4, 1893. Serial No. 460,953. (No model.)

To all whom it may concern:

Be it known that I, AUGUST LINDQUIST, a citizen of the United States, and a resident of Chariton, in the county of Lucas and State of Iowa, have invented certain new and useful Improvements in Grave-Alarms; and I do hereby declare that the following is a full, clear, and exact description of the invention, which will enable others skilled in the art to which it appertains to make and use the same, reference being had to the accompanying drawings, which form a part of this specification.

My invention relates to improvements in grave alarms, whereby persons who are prematurely buried before life is extinct, can sound an alarm, thus notifying the cemetery officials of the fact:

The object of my invention, is not only to provide means for sounding an alarm, but also to provide an improved construction whereby fresh air is supplied to the person prematurely buried, whereby life may be sustained until help arrives.

The invention consists in the novel construction and combination of parts, hereinafter described and claimed.

In the accompanying drawings, Figure 1 is an elevation showing a grave supplied with my improved signaling and air supplying apparatus. Fig. 2 is a cross section. Figs. 3, 4, 5 and 6 are detail views.

In the said drawings the reference numeral 1, designates a coffin, to contain a supposedly deceased person, which is placed in a grave as usual. Connected with the lid of the coffin, and communicating therewith is a tube 2, which extends a suitable distance above the same, and at its lower end is provided with an opening 3. Also secured to the coffin lid is an annular flange 4, of larger diameter than said tube, with which engages the lower end of a pipe 5, which encircles and extends somewhat above the upper end of tube 2. This pipe consists of a series of vertical slats 6, pivotally connected together, so as to be collapsible to enable it to be withdrawn after the coffin has been in the grave such a length of time as will absolutely assure the death of the

occupant. It will be noted that two of the 50 said slats are not in any way connected and that their adjoining ends are beveled.

Connected with the tube 2 is a vertical tube 8, having a bayonet joint 9, with which the pin or stud 7 on pipe 2 engages. This tube 8 55 extends up above the ground, and is provided with a housing 10, in which is located a rock-bar 12 carrying a bell 13, and also provided with a lever 14, having a cord or rope 15 secured to its end which passes down through the tubes 2, and 8 into the coffin within easy 60 reach of the object contained therein. This housing is provided with a door by which access may be had thereto. A downwardly extending pipe 16 corresponding with pipe 5, is 65 secured to the bottom of the housing.

The operation is as follows: When a coffin is lowered into a grave, and before the latter is filled in, the tube 2 is connected with the coffin, and the lower end of pipe 5, inserted 70 within the flange 4, and encircling said tube. The tube 8 is then connected with tubes 2 by means of the bayonet joint and the lower end of pipe 16, engages over the upper end of pipe 5. The dirt or soil is then filled in as 75 usual. It will be seen that the cord 15 extends down into the coffin, and in case the supposed corpse should have been in a trance, and not dead, when regaining consciousness 80 can grasp the cord and sound an alarm. At 80 the same time fresh air will be admitted to the coffin through the tubes, whereby life may be sustained until help comes. After a sufficient length of time has elapsed, so that it will be positively certain that death has taken 85 place, the housing and the tube 8, can be disconnected from tube 2 by giving the same a partial revolution so that they may be removed for duty elsewhere. Also owing to the collapsibility of the pipe 5, it can also be readily removed. By this means, the apparatus 90 can be readily used over and over again.

Having thus described my invention, what I claim is—

In a grave alarm, the combination with a 95 tube adapted to be secured to a coffin, and provided with a pin or stud at its upper end, of the housing having a rock-bar, a bell and

a lever, and a cord, and provided with a tube having a bayonet-joint engaging with said stud, and a downwardly extending pipe encircling said tube, and a collapsible pipe, the 5 lower end of which engages with a flange secured to the coffin, and encircling the tube secured thereto, substantially as described.

In testimony that I claim the foregoing as my own I have hereunto affixed my signature in presence of two witnesses.

AUGUST LINDQUIST.

Witnesses:

OLOF FRIEDBURG,
CARL JOHNSON.
